UNITED STATES PATENT OFFICE.

ROSWELL T. SMITH, OF NASHUA, NEW HAMPSHIRE.

EMBROIDERING-MACHINE.

SPECIFICATION forming part of Letters Patent No. 416,811, dated December 10, 1889.

Application filed June 2, 1887. Serial No. 240,053. (No model.)

To all whom it may concern:

Be it known that I, ROSWELL T. SMITH, a citizen of the United States, residing at Nashua, in the county of Hillsborough and State of New Hampshire, have invented certain new and useful Improvements in Embroidering-Machines, of which the following is a specification.

My present invention relates to that class of mechanism shown and described in an application for Letters Patent filed by me the 30th day of March, 1887, Serial No. 233,028, said machine being intended for the production of ornamental designs and trade-marks, in which the pattern consists of a comparatively small group of isolated figures. In the prior invention the work is executed by a sewing-machine of any known construction, and the several adjustments of the tambour-frame are effected by means of slides moving in right lines and at right angles to each other, the required movements being communicated to the tambour-frame through pulleys of different diameter, whereby the exaggerated movements of the motor-arm or tracer are diminished and the pattern or executed design is reduced to the required size. The stitches in which the designs are worked may be of the same or of unequal lengths, and between each stitch formation the action of the sewing mechanism is stopped automatically to permit the ensuing stitch formation.

In this mechanism the relative size of the patterns and designs or finished work can only be varied by shifting the pulleys interposed between the tracer or motor arm and the support for the tambour-frame. The mechanism also is somewhat cumbersome in comparison with the pantograph, and changes or variations in the size of the worked figure relatively to the pattern cannot as easily and quickly be made.

It is the object of my present invention, therefore, to substitute for the devices by which the stitch adjustment is effected a pantograph apparatus which is free from the objections usually pertaining thereto. Pantographs have long been used in embroidering-machines, and I propose to employ in the

present case any known construction thereof which may answer my purpose.

The invention consists in the several novel features of construction and new combinations of parts hereinafter fully set forth, and 55 definitely pointed out in the claims which follow this specification.

Referring to the accompanying drawings, Figure 1 is a plan view of a machine embodying my invention. Fig. 2 is a partial vertical section in the line 2 2, Fig. 1. Fig. 3 is a vertical section in the line 3 3, Fig. 1. Fig. 4 is a side elevation of the automatic stopping and starting mechanism. Fig. 5 is a vertical section of Fig. 3, taken in the axial line of 65 the shaft. Fig. 6 is a partial plan view of Fig. 4. Fig. 7 is a detail perspective of the shipper-arm by which the driving-pulley is unclutched from its shaft at each revolution.

In the said drawings the reference-numeral 70 1 denotes the machine-table of any suitable dimensions and shape, upon which the sewing and stitch-adjusting mechanism is arranged. The former is not essentially different from that shown and described in my 75 former application, No. 233,028, save in the particulars hereinafter specified.

The fabric is stretched upon a tambour-frame 2 of rectangular form and having upon one side an adjustable plate 3, on which the 80 hooks 4 are placed. Through a lug 5 upon this plate is tapped a set-screw 6, having bearing in a post 7 on the frame, whereby a strain is imparted to the web in one direction. Upon one arm of the tambour-frame are formed or 85 mounted lugs 8, said lugs being provided with holes, by which it is attached to a rod or bar 9, the latter having pins 9^a, which engage the holes in said lugs and enable the tambour-frame to be instantly engaged with and disengaged from its connection. This rod is attached at a point between the lugs 8 to the directing-arm 10 of the pantograph. Rising from the table 1 at points separated from each other as far as practicable are guides 95 11, in which slide parallel bars 12, arranged at right angles to the rod 9. These bars 12 carry upon their ends short sleeves 13, in which the rod 9 moves freely in the direction of its length. The arm 10 of the pantograph 100

is connected with the cross-arm 14 by a pivot-joint 15, the pivot-bolt of which passes through the end of the directing-arm 10 and thence through a plate 16, having rigid connection 5 with the rod 9, carrying the tambour-frame 2. Beneath the table in rear of the rod 9 are drop-brackets 17, in which is journaled a shaft 18, carrying two pulleys 19 of equal diameter and arranged directly beneath and in the 10 same planes with the bars 12. These pulleys lie in slots 20 in the table and rise in said slots to a point about in the plane of the table-surface or a little above the same, so that the rounded bars 12 may lie in the grooves in 15 their peripheries. Around each pulley are carried wire cables 21, attached at their ends to the bar 12, the said ends of the cable being carried past each other for attachment, as shown in Fig. 3. At their other ends they 20 are connected to posts 22, standing in a notch 23 in the periphery of the pulley, and by turning said posts the cables may be drawn tight in the groove, the construction being similar to that employed in attaching and tuning the 25 strings of a piano. The construction of the other pulley and its accessory parts is precisely the same as that hereinbefore described.

The arm 10 of the pantograph, besides being pivoted at its end to the rod 14 and arranged at right angles thereto, is extended rearward and connected pivotally with a bar 24, parallel with the rod 14. The end of this bar 24 is extended past its pivotal connection with the bar 10, and is mounted on a 35 pivot-bolt 25, which has its seat in a strip or bracket 26, mounted on the surface of the table 1 and straddling one of the bars or rods 12. This bar is preferably supported by feet 27, to raise it sufficiently to enable it to cross 40 the rod or bar 12, with which it stands at an angle of forty-five degrees. The purpose of this feature of construction will be described presently. The bar 14 is also extended beyond the point 28, where it is pivotally connected to the motor-arm 27^a, and each one of 45 the pantograph-arms is provided with perforations 30, arranged at suitable intervals for the purpose of shifting the pivotal connections in order to increase or diminish the relative size of the executed patterns in 50 comparison with the chart on which the tracing-point 31 moves.

It will be understood that the pantograph mechanism lies and operates in a horizontal 55 plane upon the surface of the table 1, carrying the tambour-frame 2, the latter resting upon a tablet or sewing-table in an opening of which the needle reciprocates.

The sleeves 13, in which the rod or bar 9 60 moves longitudinally, are swiveled in forks 13^a, carried by the bars 12, by means of trunnions 32, tapped through the ends of the fork. The latter element has a shank 33, which is swiveled upon the end of the bar 12, as seen 65 in Fig. 3. The purpose of this construction is to enable the rod 9 to move freely in the

said sleeves without the possibility of binding therein.

The pattern is placed directly beneath the tracer 31, and by following its lines in the 70 usual manner and order the stitch adjustments will be made successively, the relative degree of movement of the tambour-frame as compared with the distance traversed by the tracer 31 being capable of control by the 75 several adjustments of the pivotal connection 25 upon the bar 26 and the corresponding shift of the remaining pantograph-connections 15, 15^a, 28, and 28^a. This will be readily understood from Fig. 1. For example, 80 the pivotal attachment of the pantograph to the bar 26 is at the point marked for convenience of designation by the fraction $\frac{1}{4}$, which indicates the extent of the movements of the tambour-frame as compared 85 with those of the tracer 31, the scale of reduction being in the proportion of one to four. It may be noted in this connection that the points at which the pivotal connections of the frame are made are indicated 90 in a similar manner on the pantograph-arms. If, now, the pivotal connection 25 be shifted to the point designated on the bar 26 by the fraction $\frac{1}{5}$, it will be seen, first, that the acting distance from the pivotal point 25 to the 95 first cross-arm 10 of the pantograph is diminished by the length of a line drawn through the former point of attachment to a second line drawn through the present pivotal point at right angles to the first line; secondly, the 100 distance between the parallel arms 14 and 24 is diminished by the same extent as the shortening of the acting distance between the pivotal point and the bar 10, while, finally, the motor-arm 27^a moves the same distance to the 105 left, thereby extending the interval between it and the arm 10, which remains in its former position. If, now, the pantograph be operated, the design will be reduced to one-fifth 110 the size of the pattern under the tracer.

The arrangement of the angular bar 26 at an angle of forty-five degrees with relation to the two rectilinear lines of action of the pantograph, and using said bar as a pivotal base for the end of the arm 24, enables me by 115 simply shifting such point upon the bar to increase or diminish the acting distances of the several members of the pantograph equally, and thereby to vary the scale on which the 120 designs are executed to any degree desired.

The sewing mechanism consists, preferably, of a sewing-machine arm 34 of the Singer type, having a shaft, a needle-head, tension, and other necessary devices. This arm and its accessories are essentially the same as the 125 devices described and shown in my application No. 233,028, hereinbefore mentioned. This portion of the mechanism therefore requires little, if any, description. I drive the sewing-machine, however, by a pulley 35, 130 mounted directly upon the shaft which drives the needle-arm in the head-block 36. These

features being similar to those fully set forth in my former application of March 30, No. 233,028, I need add no description thereof in the present case. The automatic stop mechanism also is unchanged from that shown in my former case, and is very similarly combined and operated. The pulley 35 is loose upon the shaft 37, and is driven from any convenient source of power. Mounted on the shaft 10 rigidly, close by said pulley, is a clutch-carrier 38, in which slides a clutch 39, parallel with the axis of the shaft, and normally impelled by a spring 40 to move forward into engagement with a recess 41 in the said pulley. In the clutch is formed a notch 42, and an annular groove 43 is also formed in the clutch-carrier 38, in which lies the curved or semicircular portion 44 of a shipper-arm 45, pivotally mounted on a standard 46, and 15 having a projection 47, with which a spring 48 engages, by which the circular part 44 is maintained in engagement with the groove 43.

It will be noticed that the curved part 44 is thin at the outer end and grows thicker toward the other end, as seen in Fig. 7. Consequently as the clutch-carrier 38 revolves with the shipper-arm 45, lying in the groove 43 therein, when the notch 42 in the clutch-bar makes engagement with the shipper-arm 20 the latter will draw the clutch-bar out of the recess 41 as the notch 42 rides from the thin to the thicker end of the part 44.

In order to release the clutch-bar 39 and allow it to engage with and operate the pulley 35, a wire 49 is attached to the nose 50 of the shipper-arm and to a latch-bar 51, with which engages a latch 52, pivotally mounted on a key 53 and normally thrown by a spring 54 into engagement with the latch-bar 51. 25 The key 53 is pivoted upon the foot of the standard 46, and is normally raised to engage the latch 52 with the latch-bar 51 by means of a spring 55. A finger-plate 56 is mounted on the end of the key, whereby the operator 30 may at any time depress the key and release the clutch.

In order to insure the automatic disengagement of the clutch after each stitch formation, I place on the clutch-carrier 38, close to the 35 groove 43, a cam-lug 56, which at each rotation strikes the latch 52 and throws it off the latch-bar 51, thereby permitting the latter to rise and the shipper-arm 45 to restore itself to the groove 43, as before, where it will at once withdraw the clutch and arrest the stitching mechanism. Thus if the operator inadvertently depresses the key 53 and holds the 40 same too long, the cam-lug 56 will compensate for such inadvertence and effect the necessary action without effort on the part of the operator. Although I have described these features specifically, they are the same as those shown in my application filed the 30th day of March, 1887, Serial No. 233,029.

65 By the invention thus described and shown I have an embroidering sewing-machine in

which the tambour-frame is carried and the stitch adjustments effected by a pantograph without complication of parts and with great resulting accuracy. It will readily be seen 70 that the two pulleys 19 act in perfect unison, and thereby give an adjustment of the carrier-bar 9 in a line exactly at right angles with the latter. The other adjustment in the line of the axis of said carrier-bar 9 is effected by 75 the longitudinal thrust of the bar 14, and by these two movements, or the resultants of any two of them, every possible stitch adjustment can be perfectly accomplished. It should also be noted that by combining the cables 80 21 with the pulleys 19 and bars 12 in the manner shown in Fig. 3 I may adjust the position of the rod 9 by moving either end thereof horizontally and at right angles to its axis. This is done by simply turning the 85 posts 22, one to slacken and the other to tighten the cables; hence if the rod 9 is slightly out of line from any cause its position may be easily and instantly rectified in this manner. The posts 22 also serve to give 90 proper tension to the cables. The key 53 projects toward the front and the motor-arm 27 of the pantograph is about parallel therewith, said key and arm being operated by the right and left hands, respectively. 95

By this invention I provide an embroidering mechanism which may be used as a domestic machine or in manufacturing. By the use of the clutch, which restricts the multiplied action of the stitch-forming device to 100 the will of an operator, allowing the driving-wheel to run at great speed, whereby a stitch formation may be quickly made, I am enabled to do work much more rapidly and accurately. More rapidly because without a 105 clutch device, the stitch-forming device must either stop entirely or move so slowly that the fabric may be moved while the point of the needle is above the cloth, making the time between the movements of the fabric 110 three or four times as long as that allowed for fabric adjustment. By the use of the clutch the stitch-forming device may run so fast as to practically utilize this lost two-thirds or more of time. More accurately, because without the clutch the fabric must be 115 in place at a given time before the needle reaches it, resulting in inaccuracy from lack or fear of lack of time to make a proper adjustment. With the clutch the fabric is first 120 adjusted, and then the stitch is instantly taken through the voluntary act of the operator.

When I use the words "rectilinear movements on lines in two directions," I mean, as 125 applied to the fabric-frame in such a way that if a line were drawn across the tambour-frame and another line drawn across it at right angles to the first these two lines would be held to parallel movements wherever the 130 tambour-frame is placed.

What I claim is—

1. In an embroidering-machine, the combination, with the tambour-frame and its supports and guides giving rectilinear motion in two directions thereto, of a pantograph mechanism connected to the supports of the tambour-frame, and the bar 26, having thereon a series of fulcrum-points for connection with the fixed point of the pantograph, said fulcrum-points being arranged at an angle of forty-five degrees with the two lines of rectilinear movements of the pantograph, substantially as specified.
2. In an embroidering-machine, the combination, with the stitch-forming devices and the tambour-frame, of a rod carrying said tambour-frame, guides giving true longitudinal movement to said rod, bars moving longitudinally and in unison at an angle of ninety degrees with the rod and connected at their ends to the supports in which the latter slides, and a pantograph mechanism pivotally attached to the rod carrying the tambour-frame, substantially as specified.
3. In an embroidering-machine, the combination, with a bar having studs thereon having rectilinear motion in two directions at right angles to each other, of an attachable and detachable tambour-frame moving upon a horizontal table under the needle and having perforations or openings which receive studs on the bar, and a pantograph between the said tambour-frame and the pattern-chart, substantially as specified.
4. In an embroidering-machine, the combination, with a longitudinal bar detachably connected to one side of a tambour-frame, of guides giving true longitudinal movement to said bar, rods connected to said guides and having adjustment at right angles therewith, pulleys rigid on a shaft beneath the machine-table, cables wound in opposite directions on said pulleys and attached to the said rods, and a pantograph connected to the bar moving the tambour-frame, substantially as specified.
5. In an embroidering-machine, the combination, with pulleys moving in unison, of cables attached to posts on the peripheries of said pulleys, said cables being wound thereon in opposite directions and attached at their other ends to bars moving longitudinally in the plane of rotation, bearings on the ends of said bars, a rod moving in said bearings, and a pantograph connected to said rod, substantially as specified.
6. In an embroidering-machine, the combination, with a rod to which the tambour-frame is detachably connected, of parallel bars carrying bearings for said rod, pulleys moving in unison beneath said bars, cables carried partly around said pulley in opposite directions and connected to opposite ends of said bars, and posts turning on the peripheries of said pulleys and to which the cables are attached, substantially as specified.
7. In an embroidering-machine, the combination, with a sewing mechanism and a horizontal table therefor, of a tambour-frame having perforations on one side, a rod having studs which enter said perforations, means for imparting true rectilinear movement in two directions at right angles to each other to said bar, a pantograph arranged between the rod and the pattern-chart, and the bar 26, having thereon a series of fulcrum-points for connection with the stationary point of the pantograph arranged at an angle of forty-five degrees with its two lines of movements, substantially as specified.
8. In an embroidery-machine, the combination of a tambour-frame, a pantograph which controls the movement of the tambour-frame, said frame being held to true rectilinear movements in two directions, a stitching device adapted to act upon a fabric held by the tambour-frame, and an automatic stop mechanism, whereby the needle is arrested after each stitch formation, substantially as described.
9. In an embroidering-machine, the combination, with a tambour-frame, a carrier or rod having two different rectilinear movements, and a pantograph having pivotal connection with the carrier or rod, a stitching device adapted to act upon a fabric held by the tambour-frame, of a spring-engaged shipper-lever by which the action of the sewing mechanism is automatically arrested, and a latch mounted on a key-bar to withdraw the shipper-arm and engage the revolving pulley and shaft, substantially as specified.
10. In an embroidering-machine, the combination, with a carrier-rod having rectilinear movement in two directions, of a pantograph-frame pivotally connected to the rod and having perforations at intervals in each member, and the bar 26, having thereon a series of fulcrum-points for connection with the stationary point of the pantograph arranged at an angle of forty-five degrees with the lines of both the elemental movements of the pantograph and having pivots or studs at separate points, substantially as specified.
11. In an embroidering-machine, the combination, with a carrier or rod, of guides giving longitudinal direction thereto, parallel bars carrying said bearings in a direction at right angles to the said longitudinal movement, pulleys rigid on the same shaft and rotating in unison beneath said bars, cables attached to opposite ends of each bar carried past each other and partly around the pulleys in opposite directions, and posts turning on the peripheries of said pulleys to which the cables are attached, substantially as specified.
12. In an embroidery-machine, the combination, with a tambour-frame and pantograph, of a bar or rod which holds and moves the tambour-frame and to which the pantograph is pivotally connected, said rod having true rectilinear movements in two directions through connection with sleeves which are

held to parallel movements and in which the rod has free end movement, and a stop mechanism, whereby the stroke of the needle is arrested after each stitch formation.

5 13. In an embroidery-machine, in combination with a stitch-forming device, sleeves held to true parallel movements, a rod sliding freely in and held to parallel movements by said sleeves, a tambour-frame secured to the
10 rod and sharing all its movements, a panto-

graph pivoted to the rod and controlling its action, substantially as described.

In testimony whereof I have hereunto signed my name in the presence of two attesting witnesses.

ROSWELL T. SMITH.
